TELEPHONE SYSTEM USING SINGLE-MOTION NUMERICAL SWITCHES

Frederick L. Kahn, Chicago, Ill., assignor to General Telephone Laboratories, Incorporated, a corporation of Delaware

Application May 11, 1953, Serial No. 354,090

14 Claims. (Cl. 179—17)

This invention relates to telephone systems and more particularly, numerical switches, such as selectors and connectors, of the single-motion stepping type in such systems.

Generally speaking, single-motion switches are simpler in mechanical design than two-motion switches and require a lesser number of different parts for their manufacture and maintenance. They also have the advantage of providing greater flexibility as to the number and size of the groups of outlets that can be connected to their banks. On the other hand, unless registers are employed for storing the various digits, numerical switches of the single-motion type require the switch wipers to be advanced in response to a group-selecting series of impulses over outlets of unwanted groups to a position within, or immediately preceding, the wanted group in good time before the arrival of the next impulse series.

In order to more safely meet this requirement it has previously been proposed to let the switch execute this group-skipping movement even while the group-selecting series of impulses is being received. For example, in U. S. patent application Serial No. 350,688, filed by C. E. Lomax on April 23, 1953, an arrangement has been disclosed in which interrupter circuits for the switch magnet are completed during the group-selecting digit under the joint control of the impulse relay and a control wiper and bank of the switch. This control bank has a number of sets of consecutive control contacts, each set in the switch positions corresponding to an associated group of outlets and the advancement of the switch is controlled by two control conductors, one multiplied to the first and the other multiplied to the last contact of the various sets. The two control conductors are alternately energized, one upon each restoration and the other upon each re-operation of the impulse relay, and the intermediate control contacts of each set are directly wired to a stepping potential. In U. S. patent application Serial No. 352,370, filed by A. H. Faulkner on May 1, 1953, a modification of this group-skipping control arrangement has been shown in which use is made of the group-staggering scheme disclosed in patent application Serial No. 351,086, filed by C. W. Frank on April 27, 1953.

In the arrangements according to both Lomax and Faulkner the group-skipping movement of the switch is coordinated with the dial pulses in such a way that the switch although rapidly advanced, is kept from overrunning the numerical pulses. Because of the multiple connection of the above-mentioned control conductors to the various sets of control contacts such overrunning would result in a false setting of the switch. The present invention also employs two alternately energized control conductors are multiplied as between various sets of control contacts. However, it is an object of the invention to provide an arrangement of this general type in which the switch is not only kept from overtaking the dial pulses but in which the margin of safety provided by the above patent applications in case the switch, for some reason, temporarily lags behind these pulses, is further increased.

2

Another object of the invention resides in the provision of means whereby the switch is prevented from being stepped off-normal if no group-selecting pulses are received.

5 In accordance with one feature of the invention one of the two control conductors is multiplied to contacts in the control bank of the numerical switch in the start positions of odd-numbered groups and the other control conductor to contacts in that bank in the start positions of even-numbered groups. These control or start conductors are alternately connected up by odd-even control means governed by the impulse relay so that one of these control or start conductors is energized on the various odd impulses and the other on the various even impulses of the group-selecting digit, the remaining contacts of the control bank being directly wired to a stepping potential. In the preferred embodiment disclosed herein in which the invention is illustrated as applied to a party-connector the aforementioned odd-even control is provided by an auxiliary single-motion stepping switch. This auxiliary switch is first set under the control of a station digit to select a given mode of ringing for the purposes of party-selection, and after being reset is again advanced one step per impulse, during the group-selecting or tens digit to assist in 15 setting the connector switch proper on the start position for the desired tens group of lines. During the last or units digit the connector is then further advanced under the direct control of the impulse relay and on a one-step-per-impulse basis, to the position accommodating the desired line in the selected tens group.

In accordance with the principles of the abovementioned Frank application the numerical switch has two sets of wipers and contact banks, one bank accommodating the odd groups of outlets and the other accommodating the even groups of outlets but in staggered relation with respect to the odd groups. Thus, if each group comprises ten outlets, the start positions for any two consecutive groups such as 2 and 3 need only be five positions apart and consequently the numerical switch needs to be advanced over only five positions in response to a given dial pulse of the group-selecting digit. At the end of this digit the odd or even wiper set is made effective depending on whether this digit is odd or even and according to one feature of the invention this control is effected by means 35 of the odd-even control means mentioned above.

In accordance with another feature of the invention and in line with the second of the above-named objects, there is provided a relay for absorbing the first impulse of the group-selecting digit. This prevents the switch from being 50 stepped off-normal when no group-selecting impulses are received, and it also makes it possible to connect the outlets of group 1 to the beginning of the connector switch bank.

The invention both as to its organization and method 55 of operation together with other objects and features thereof, will best be understood by reference to the following specification taken in connection with the accompanying drawings. In these drawings:

Fig. 1 shows part of the circuit diagram of a connector 60 according to the invention; a substation and associated subscriber's line, and a rotary line switch connecting this line with the connector also are shown, schematically, in this figure.

Fig. 2 illustrates the remaining part of the circuit diagram of the connector and shows, in particular, the magnet, wipers and banks of the connector switch and of the auxiliary switch associated therewith; this figure also shows a party line and two substations connected to this line.

70 Fig. 3 is a straight-line presentation of some of the banks of the connector switch; this figure illustrates the way in which the various groups of lines are accommodated.

dated in the odd and even set of banks and shows the wiring of the group control bank of this switch in relation to this line assignment.

In order to form a complete system, Fig. 2 should be placed to the right of Fig. 1.

General description

A brief description of the apparatus involved in the illustrated embodiment of the invention will first be given.

Referring first to Fig. 1, there is shown a substation A and its associated subscriber's line 11. This subscriber's line has access, by way of a line switch 20 individually associated therewith, to connectors such as that shown in the main portion of Fig. 1 and in Fig. 2 and may in time be reached over the banks of these connector switches. The line switch 20 is assumed to be of the conventional absence-of-ground searching rotary stepping type, a circuit for a switch of this kind being shown in detail for example, in United States Patent 1,620,113 to C. E. Lomax. It should be understood, however, that non-numerical switches of a different type such as line finders could also be used instead of line switches for connecting the subscribers' lines to a connector; and that further switching stages including, for example, a single-motion selector employing a group-skipping control of the general type shown for the connector, Figs. 1 and 2, could be interposed between the non-numerical switch and the connector. In this connection reference is made, for example to the above-mentioned patent application of A. H. Faulkner in which the same general arrangement is used for the group-skipping control of a rotary type selector and connector.

While the relays associated with the connector are shown in the main portion of Fig. 1, the connector switch itself is illustrated in Fig. 2. This connector switch is of the fast-stepping rotary type, preferably of the general design disclosed in United States Patent 2,522,715 to K. W. Graybill et al., and has a stepping magnet 70 and interrupter contact 71, each step being taken at the time magnet 79 is de-energized. As shown in Fig. 2 the switch also has two sets of pairs of talking and test wipers which are designated +01, +2; -01, -02; CO1, CO2 for the left-hand or odd set and +E1, +2; -E1, -E2; CE1, CE2 for the right-hand or even set, together with the associated 25-point semi-circular talking and test banks, and the switch further mounts a pair of group control wipers and banks, designated GC1, GC2, which is common to the aforementioned two sets.

The wipers of the connector switch are single-ended but are connected together in pairs, the two wipers of each pair respectively co-operating with the two banks of the associated bank pair but being circumferentially displaced by 180 degrees with respect to each other. As shown in the above-mentioned Graybill et al. patent and as indicated in the present Fig. 2, the wiper collector springs are mounted in the switch position immediately in back of the first bank position proper; and, as permitted by the design of the Graybill switch, there is provided in both group control banks GC1, GC2, Fig. 2 an additional or 26th bank contact in this position of the wiper shaft, namely at a point diametrically opposite the location of the wiper collector springs. No such 26th bank contact is provided in the twelve talking and test banks. Thus, as one wiper of a pair of talking or test wipers moves off the end of its bank or level, the other wiper of the pair moves into the position immediately preceding the first bank contact of its level. The additional or 26th contact in the two group control banks serves to automatically advance the connector switch over this vacant position when certain tens or units digits are dialled, and also serves to initially advance the switch from its normal position. In this connection attention is directed to off-normal contacts 75 which as indicated in Fig. 2, are opened in the 52nd position of the wiper

shaft, i. e. when GC1 wiper 76 rests immediately in back of the first bank contact of the associated bank.

The numerals shown in the various positions of the talking and test banks, Fig. 2, represent the numbering 5 of the lines connected to these positions; and the same is true for the lower portion of Fig. 3 where the two pairs of test banks CO1, CO2 and CE1, CE2 have been shown developed into rectilinear form to more clearly illustrate the line allocation, the allocation of the lines in the talking banks, of course, being the same as that shown for the test banks. It will thus be seen from Figs. 2 and 3 that there are provided ten groups of ten lines each and numbered 11-10, 21-20, 31-30 and so on, the odd-numbered groups being connected to the odd set of banks CO1, CO2 etc., and the even-numbered groups being connected to the even set of banks CE1, CE2 but in staggered relation to the odd-numbered groups. By way of example, a party line designated 96 and having substations B and C connected thereto, is shown in Fig. 2 as accessible over the fourth position of group 3 which is accommodated in connector switch bank +01, -01 and CO1.

The wiring of group control banks GC1 and GC2 as shown in Fig. 2 and the upper portion of Fig. 3 serves 25 to advance the connector switch in response to the tens or group-selecting digit into the position, called start position herein, which is immediately in back of the position accommodating the first line of the wanted group. As shown in Figs. 2 and 3, the contacts in both group 30 control banks corresponding to the start positions of all odd groups except 1 are multiplied to odd start conductor PO, and those corresponding to the start positions of all even groups except 0 are multiplied to even start conductor PE. Contact 26 in the GC1-bank is wired to direct ground, contact 26 in the GC2-bank is wired to conductor GS, contacts 20-25 in the GC2-bank are left blank and all remaining contacts in both control banks are connected in multiple to conductor GR.

The auxiliary switch shown in the left portion of Fig. 2 40 also is of the fast-stepping rotary type. This switch also is indirect-stepping, i. e. the switch steps upon the de-energization of its magnet 60. This switch may likewise be of the general design disclosed in the Graybill patent referred to above except that it is assumed herein that the switch has three 10-point contact banks A1, A2 and A3 each engaged by a double-wiper. Bank A1 serves to alternately connect up start conductors PO and PE, bank A2 to control the operation of odd-even wiper switching relay 180, Fig. 1, and bank A3 controls the operation of side-of-line switching relay 130 and also serves as a homing bank. The auxiliary switch further has an interrupter contact 61 and an off-normal contact 65.

Detailed description

A detailed description of the operation of the system illustrated in the drawings will now be given. For the purposes of this description it will first be assumed that the subscriber at substation A, Fig. 1, initiates a call to subscriber B whose directory number is 934.

When the subscriber at substation A lifts his handset from the cradle a loop circuit is closed across his line 11 in the usual manner, whereby line switch 20 which is associated with this subscriber's line is started in search for an idle connector marked by the absence of ground on its test conductor C and a guarding ground is placed on CN-conductor 14 to guard the line against seizure from a connector. Line switches of the absence-of-ground searching type are well known in the art, a typical circuit of this kind being described, for example, in the above-mentioned United States Patent 1,620,113 to C. E. Lomax. Assuming that the connector shown in Figs. 1 and 2 is the first idle connector encountered by line switch 20, this switch is arrested in the corresponding position. The line 70 is now switched through in the line switch in the manner

well known in the art so that the following loop circuit is closed to line relay 110 in the connector substation A, subscriber's line 11, switching contacts, not shown, and talking wipers 21, 22 and associated banks of line switch 20, line conductors 15, 16, contacts 117, 119, upper and lower winding of line relay 110, to battery and ground respectively. Furthermore, dial tone is returned to the calling subscriber by way of dial tone conductor 48, condenser 47, contacts 201, 146 and 137a, condenser 54 and negative line conductor 15.

Line or impulse relay 110, in operating, at contact 111 causes the operation of hold relay 120 over an obvious circuit. When relay 120 operates it connects ground at contact 127 to incoming test and hold conductor 17 to hold the cut-off relay, not shown, of line switch 20 in operated condition and mark the connector as busy in the line switch banks.

The calling subscriber now actuates his calling device in accordance with the first or station digit 9, of the called subscriber's number. Upon each release of line relay 110 during the receipt of this digit and each of the subsequent two digits, the circuit of relay 120 is opened at 111, but relay 120 due to its slow-release characteristic stays operated during each impulse series. When impulse contact 112 closes upon the first release of relay 110 responsive to the receipt of the first impulse of the station digit the following circuit is closed for magnet 60 of the auxiliary or station selector switch, Fig. 2: ground, contacts 112, 125, 192, 195, 203, conductor 215, winding of magnet 60, battery. A branch of this circuit extends through the winding of digit-supervisory relay 160, thereby causing the operation of this relay. Relay 160 operates at the beginning of each impulse series and, being slow-to-release, remains operated until the end of the respective series, in spite of the intermittent interruptions of its circuit at impulse contact 112.

Upon the first re-operation of relay 110 at the end of the first impulse of the station digit, the above-traced circuit of auxiliary switch magnet 60 is opened at contact 112 so that this magnet releases thereby advancing the auxiliary switch into position 1 and hence causing the actuation of off-normal contact 65. Each subsequent release and re-operation of line relay 110 during the first digit similarly advances the auxiliary switch on a one-step-per-impulse basis so that this switch at the end of the station is arrested in position 9. Digit supervisory relay 160 now restores with a slight delay, thereby at its contact 163 completing the following circuit for side-of-line switching relay 130 in series with the lower winding of relay 200: ground, contacts 197, 163, 178, 205, conductor 217, A3-wiper 68 of the auxiliary switch in position 9, conductor 229, lower winding of relay 200, winding of relay 130, battery. Relay 130, upon operating in this circuit, at its preliminary or "X" contact 134a locks to ground at contact 124 and at its contacts 131, 132 and 133, 134 reverses the connections of ringing generator and of battery through the lower winding of ring cut-off relay 135 with respect to the two sides of the line, thereby preparing the signalling of substations such as B, Fig. 2, whose ringer is connected to the negative side of the line.

Relay 200 also operates in the above circuit. This relay at its preliminary or "X" contact 207 locks to ground at contact 124 by way of its upper winding, thereby connecting ground to contacts 1-8 and 10 auxiliary switch bank A3; at contact 201 opens the dial tone circuit; at 202 prepares group control circuits extending over auxiliary switch wiper A1; at 203 disables the above-traced impulse circuit for magnet 60; at 204 prepares a circuit to the lower winding of pulse-absorbing relay 170; at 205 disconnects the A3 wiper, thereby opening the above-traced operating circuit of relays 130 and 200; and at 206 closes the following re-setting or homing circuit for auxiliary switch magnet 60: ground, contacts 197, 163, 178, 206, off-normal contact 65, interrupter contact 61, winding of magnet 60, battery. The auxiliary switch is accord-

ingly automatically advanced, under the control of interrupter contact 61 until off-normal contact 65 opens upon the switch reaching its normal position. The auxiliary switch is now ready to be again advanced in response to the second or tens digit of the called subscriber's number in the manner described below.

When the calling subscriber now actuates his dial in accordance with the second or tens digit, 2, of the called subscriber's number, the first release of line relay 110 10 incident to the receipt of the first impulse of this digit causes the lower winding of 2-step relay 170 to be energized by way of the following circuit: ground, contacts 112, 125, 192, 195, 204, 174, lower winding of relay 170, to battery. Relay 170 which as a result of the mere energization of its lower winding operates to its first step, closes its "X" contact 172. This prepares the energization of the upper winding of relay 170, but at this time the last-mentioned winding is still short-circuited by ground extended by way of the last-traced circuit. Digit 15 supervisory relay 160 operates from ground through contacts 112 and 125 as before.

When impulse contact 112 opens incident to the re-operation of relay 110 at the end of the first impulse, direct ground is removed from the left-hand terminal of 25 both windings of relay 170 so that this relay is now energized, from ground through contacts 122 and 166 over both its windings in series. Relay 170 now operates to its second step, thereby actuating its remaining contacts. At 174 relay 170 opens another point in the 30 above-traced energizing circuit for its lower winding, and at 173 and 175 prepares circuits for both switch magnets 60 and 70. The second and any following impulses of the tens digit are, therefore, routed into the magnets of both switches as will now be explained.

35 Upon the second release of line relay 110 incident to the receipt of the second impulse of the group-selecting or tens digit 3 the following circuits are closed for the auxiliary and connector switch magnets: ground, contacts 112, 125, 179 or 192, 195, 204, 173 and from there 40 on the one hand by way of conductor 215 to auxiliary switch magnet 60 and battery, and on the other hand by way of contact 175, GS-conductor 216, GC2-wiper 77 in the 52nd or normal position of the connector switch, interrupter contact 71, connector switch magnet 70, battery. 45 As the above circuit for auxiliary switch magnet 60 does not include the interrupter contact 61 of this magnet, this magnet merely operates without, for the time being, advancing the auxiliary switch. However, connector switch magnet 70, in operating over the above-traced circuit, opens its own operating circuit at its interrupter contact 50 71 and upon releasing advances the connector switch into position 1. In this position another circuit, extending over GR-conductor 212, is closed for magnet 70. This circuit may be traced from ground through contact 191, conductor 212, GC-1 wiper 76 in position 1, interrupter 55 contact 71 to magnet 70 and battery. Magnet 70, in operating, opens this circuit at interrupter contact 71 and, in releasing, advances the connector switch into position 2. As GR-conductor 212 is multiplied, among others, over contacts 1-4 of the GC-1 bank, the foregoing self-interrupting action of magnet 70 continues until the connector switch has reached position 5.

60 The connector switch has been advanced, responsive to the second impulse of the group-selecting or tens digit over its positions 1-4 which accommodate lines of group 65 10 as well as 1, to position 5 which is the start position for group 2. Due to the fact that the ground connection at 191, to GR-conductor 212 includes neither a contact of relay 110 nor a wiper and bank contact of the auxiliary switch, it will be noted that the advancement 70 of the connector switch over positions 1-4 is maintained even if impulse relay 110 should re-operate in the meantime. When relay 110 does re-operate at the end of the 75 second impulse, the opening of impulse contact 112 breaks the circuit of auxiliary switch magnet 60, there-

by permitting this magnet upon its release to advance the auxiliary switch into position 1.

In position 1 of the auxiliary switch the control wiper A1 of this switch connects up start conductor PE which is connected to 5th contact in the GC1-bank of the connector switch corresponding to the start position of group 2 and in multiple therewith, to GC1 and GC2-bank contacts in the start position of other even groups. However, the self-interrupter circuit for connector switch magnet 70 extending over this start conductor and bank contact cannot be completed until line relay 110 releases at the beginning of the following, that is the third, impulse of the tens digit, this circuit being traceable from ground by way of contacts 112, 125, 179 or 192, 195, 204, 173, 193, 202, conductor 213, A1-wiper of the auxiliary switch in position 1, conductor PE, GC1-wiper 76 of the connector switch in position 5, interrupter contact 71, magnet 70, battery.

It will be seen, therefore, that if the connector switch, for some reason such as accidental jamming of the switch mechanism in any of positions 1—4, is slow in reaching position 5, no harm is done provided only that the switch has reached this position at the time, or immediately before, impulse relay 110 re-operates at the end of the third impulse. This in effect allows the connector switch a time interval for stepping past positions 1—4 under such an unstandard condition which roughly corresponds to the sum of two break periods and one make period of the dial pulses. Under ordinary conditions, however, the switch will be slightly faster than the dial and will, therefore, be temporarily arrested in start positions such as 5 pending the receipt of the following impulse. In this connection it is pointed out that a stepping switch of the type used herein normally advances its wipers at a rate of roughly 75 steps per second when operated in a self-interrupting circuit so that assuming a dial speed of ten impulses per second the switch is capable of taking approximately 7.5 steps between any two impulses of the group selecting series. Inasmuch as the connector switch of the present embodiment is required to skip only 5 or in one instance 6 positions in the time between two impulses, the switch is, under ordinary circumstances, well able to keep up with the dial pulses.

When connector switch magnet 70 is re-operated in position 5 upon release of relay 110 incident to the receipt of the third impulse, the switch is at once advanced, under the control of interrupter contact 71, into position 6. Since contacts 6—9 of the GC1-bank are again wired to direct ground by way of GR-conductor 212 and closed contact 191, the switch is immediately further advanced by self-interrupting action until it reaches position 10 which is the start position of group 3; and the auxiliary switch is stepped into position 2 as soon as impulse contact 112 opens upon the re-operation of line relay 110 at the end of the third impulse, thereby connecting up the other start conductor PO.

Should the tens digit contain further impulses it will readily be seen that the connector switch would be stepped off position 10 by the energization of its magnet, by way of auxiliary switch wiper A1 in position 2 and start conductor PO responsive to the receipt of the fourth impulse, the stepping action of the connector switch subsequently being maintained from ground via GR conductor 212 until the switch reaches position 15 which is the start position for group 4. In a similar fashion the connector switch would upon receipt of a fifth impulse be stepped off position 15 due to its magnet being energized via auxiliary switch wiper A1 in position 3 and start conductor PE, and in this case too, the stepping operation of the connector switch would thereafter be maintained, independent of the condition of the impulse relay, while the switch reaches the next following start position, in this instance position 20. Thus, the auxiliary switch is advanced one step upon each re-operation of the impulse relay following the first, and the connector switch is

advanced, five or in one case six steps upon each release of the impulse relay following the first, namely due to the alternate energization of start conductors PE and PO and the connection of the intermediate GC1 and GC2 contacts to direct ground. The sixth step above referred to is taken by the connector switch in skipping switch positions 26—30 in response to the seventh impulse of tens digit 7, 8, 9 or 0, due to ground being directly connected to the 26th contact in the GC1-bank of the switch.

As in the present example it was assumed that the tens digit is 3, the auxiliary switch is arrested in position 2 and the connector switch in position 10 and relay 160 restores with a slight delay at the end of the digit. Relay 160, in releasing, at contact 163 closes the following circuit for relay 190: ground, contacts 197, 163, 177, winding of relay 190, battery. Relay 190, upon operating, at its preliminary or "X" contact 198 locks to ground at contact 124; at contact 197 opens its operating circuit; at contact 191 removes ground from GR conductor 212; at 193 disables wiper A1 of the auxiliary switch; at 194 prepares a circuit for odd-even wiper switching relay 180 which circuit, however, can only be completed if wiper A2 of the auxiliary switch at the end of the tens digit rests in any of positions 1, 3, 5, 7 or 9; at 195 disables the above-traced group control circuit for the two switch magnets; and at 196 prepares an impulse circuit for the connector switch magnet which extends over the winding of relay 165 in series.

The calling subscriber now actuates his calling device in accordance with the last or units digit 4, of the called subscriber's number. Upon the first release of line relay 110 incident to the receipt of the first impulse of this digit the following circuit is closed for relay 165 and magnet 70 in series: ground, contacts 112, 125, 179, 196, winding of relay 165, conductor 221, winding of magnet 70, battery. Magnet 70 operates in this circuit but without effect at this time. Series relay 165 also operates, thereby at its contact 168 closing a locking circuit for itself independent of contact 179, and at 166 opening the locking circuit of relay 170. This relay, in restoring at 171 closes a point in the test circuit and at 176 connects ground via contacts 122 and 167 to GS-conductor 216. Relay 160 also operates on the first impulse of the digit so that the upper winding of busy relay 140 is connected to odd test wiper CO1 by way of contacts 162, 129, 171, 185, conductor 235, CO1-wiper 82. However, while relay 140 may operate with test wiper 82 in position 10 or in any of the following positions that this wiper assumes during the receipt of the units digit, such operation of the busy relay is without effect at this time, since due to the slow-release characteristic of relay 160 the locking circuit of relay 164 is open at contact 164 during this digit. Series relay 165 likewise is of the slow-releasing type and, therefore, remains operated throughout the digit.

Reverting to the operation of connector switch magnet 70, this magnet restores upon the opening of impulse contact 112 at the end of the first impulse, thereby advancing the switch to position 11 which accommodates the first line of tens group 3. In a similar manner this switch is advanced in response to the remaining three impulses of the digit on a one-step-per-impulse basis so that the switch at the end of the digit comes to a rest in position 14. Since because of the failure of wiper switching relay 180 to operate, the odd wiper set has been made effective, access is now obtained over this set of wipers to subscriber's line 96 which represents the fourth line in tens group 3.

It will first be assumed that the called subscriber's line is idle at this time so that test conductor 99 is free of ground. Accordingly busy relay 140 cannot operate by way of contact 162 with the connector switch set on this line. Both relays 165 and 160 release at the end of the digit with a certain delay. Relay 165, in restoring, at 168 disables the impulse circuit. When relay 160 releases, the following circuit is closed for switching relay

150 in series with the cut-off relay in the called line circuit: ground, contacts 122, 142, lower winding of relay 150, contacts 161, 129, 171, 185, conductor 235, CO1-wiper 82 in position 14, test conductor 99, and thence through the winding of the cut-off relay, not shown, associated with the line switch of the called line, to battery. The line cut-off relay operates in this circuit, thereby clearing the called party line from attachments. Switching relay 150, Fig. 1, also operates. At contact 156 the relay closes a locking circuit for itself extending from ground at contact 122 through contact 156 and the upper winding of relay 150 to battery; at 153 it establishes a short-circuit extending through contact 142 across its lower winding, thereby connecting direct ground to test wiper 82 and accordingly busying the called line in the connector banks; at 155 connects a multiple ground to hold conductor 17; at 157 connects ring-back tone to the calling end of the connection, by way of ring-back tone conductor 42, condenser 41, contacts 157, 208, 146, 137a, condenser 54 and negative line conductor 15; and at 151 and 152 switches the ground-connected generator and the battery-connected lower winding of ring cut-off relay 135 through to the negative and positive side respectively of the called party line.

Ringing current is now projected over the negative side of the line by way of the following circuit: ground-connected ringing generator, not shown, conductor 56, contacts 132, 136, 151, 181, conductor 231, connector switch wiper 80 in position 14, negative conductor 98 of called party line 96, ringer and condenser, not shown, at substation B, ground. The ringer at this substation accordingly is actuated but the one at substation C is not since the last-mentioned ringer is connected to the positive side of the line. When the subscriber at substation B hears his ringer being sounded he answers the call by lifting his handset from the cradle. This establishes the following loop circuit over the called line: ground-connected generator, contacts 132, 136, 151, 181, conductor 231, wiper 80, conductor 98, switchhook contact, not shown, at substation B, and back over conductor 97, wiper 78, conductor 233, contacts 183, 152, 138, 134, lower winding of relay 135, battery.

Ring cut-off relay 135 in operating over this loop circuit, at its preliminary or "X" contact 139a, closes a locking circuit for itself which extends from ground through contacts 122 and 139a and the upper winding of relay 135 to battery, thereby insuring the full operation of this relay. At its contact 137a the relay opens the ring-back tone circuit, and at contacts 136, 137 and 138, 139 it transfers the negative and positive side of the called line from ringing generator and cut-off battery to battery through the upper winding and ground through the lower winding of back-bridge relay 115 respectively, thereby providing transmission battery for the called subscriber's transmitter. Relay 115 operates in this loop circuit and, in doing so, reverses, at contacts 116, 117 and 118, 119, the battery polarity of the calling loop. This current reversal may be used for purposes of metering or of answering supervision to an operator in the well known manner, the corresponding facilities having been omitted from the drawings as they form no part of the invention.

The calling subscriber at substation A and the called subscriber at substation B may now enter into conversation. When the calling subscriber replaces his receiver at the end of the call, line relay 110 releases, permitting relay 120 to restore. Relay 120, in releasing, at contact 128 removes a multiple ground from hold conductor 17; at 129 disconnects the test wiper so that the called party's cut-off relay restores; at 121 short-circuits the lower winding of busy relay 140, thereby rendering this relay slow-to-release; at 123 prepares an alternative circuit for the last-mentioned relay; at 124 opens the locking circuits of relays 130, 180, 190 and 200, thereby permitting these relays to restore; at 122 interrupts the

locking circuits of relays 150, 115 and 135, whereby these relays are also permitted to restore; and at 128 closes a homing circuit for the auxiliary switch extending from ground through contact 128, conductor 218, off-normal contact 65, interrupter contact 61, winding of magnet 60, to battery. With both relays 120 and 150 released, a homing circuit is also closed for the connector switch itself. This circuit may be traced from ground through contacts 112, 126, 154, conductor 222, off-normal contact 75, interrupter contact 71, magnet 70, to battery. A branch of this circuit extends from the junction of contacts 75 and 71 by way of conductor 223 and contact 120 to the upper winding of busy relay 140 and battery, whereby relay 140 is operated under the control of off-normal contact 75.

Both switches are now, simultaneously, advanced due to the action of their respective interrupter contacts, this self-interrupting action being stopped upon the opening of off-normal contacts 65 and 75 in the respective home 20 positions of the switches. When off-normal contact 75 opens, the circuit of the upper winding of relay 140 is broken and this relay releases with a delay due to the short-circuiting of its lower winding, thereby giving the auxiliary switch and the other relays of the connector sufficient time to restore. At contact 145 relay 140, in restoring, removes ground from hold conductor 17, whereby the cut-off relay, not shown, in the calling subscriber's line circuit is permitted to restore. The connector is now available again for further calls.

30 In the above description of a call from substation A to substation B it was assumed that the called subscriber's line was idle. Assuming now that this line is busy in an outgoing or incoming call, then the following circuit is closed to busy relay 140 during the release time of 35 relay 160 at the end of the units digit: ground on test conductor 99, connector switch wiper 82 in position 14, conductor 235, contacts 185, 171, 129, 162, upper winding of relay 140, to battery. This operating circuit of relay 140 is broken at 162 upon the release of relay 160 but shortly before that the following locking circuit for this relay is completed at contact 164: ground, contact 122, actuated contact 143 of relay 140, contact 164, upper winding of relay 140, to battery. Relay 140, upon operating, also connects busy tone to the calling end of the 40 connection, namely by way of busy tone conductor 58, condenser 57, contacts 141, 137a, condenser 54, and negative line conductor 15; and at contact 145 connects a multiple ground to hold conductor 17.

The receipt of busy tone induces the calling subscriber 50 to replace his handset, whereupon relays 110 and 120 release in this order. Relay 120, in restoring at 127 removes a multiple ground from hold conductor 17; at contact 124 permits relays 139, 190 and 200 to release; at contacts 122 opens the above locking circuit of relay 55 140; and at 128 and 126 closes the above-traced homing circuits of the auxiliary switch and connector switch respectively so that these two switches begin their homing operations. During the homing operation of the connector switch, busy relay 140 is held in the above-traced 60 alternative circuit extending through contact 120. When this circuit of relay 140 is opened at off-normal contact 75, the relay restores with a predetermined delay due to the short-circuiting of its lower winding by way of contacts 121 and 144, thereby at 145 removing ground from 65 hold conductor 17 to cause the release of the preceding equipment.

The foregoing description was primarily concerned with the functioning of the connector when 934, the directory number of substation B, is dialled. The operation 70 of the connector under various other conditions of dialling will now briefly be considered. Let it first be assumed that an 0 instead of a 9 has been dialled as the first or station digit. In this case the auxiliary switch is positioned in position 10 at the end of the station digit and, accordingly, the above-traced circuit for side-of-line

switching relay 130 cannot be closed. However, relay 200 is operated over A3-wiper 68 of the auxiliary switch in position 10 and its upper winding, and this relay at 207 completes its locking circuit, causes the auxiliary switch to release and prepares the connector circuit for the receipt of the second digit as before. The following operation of the connector, therefore, is the same as above described except that, because of the unoperated condition of relay 130, ringing current is projected over the positive side of the called party line. As a result, substation C rather than B is signalled in this case.

First digits 1—8 are not used in the system described herein. Should a calling subscriber erroneously dial one of these digits in the first place, relay 200 would still be operated at the end of the first digit, due to the fact that contacts 1—8 and 0 are multiplied with each other in the A3-bank of the auxiliary switch. This switch would, accordingly, be restored to normal and also in all other respects the functioning of the circuit if further digits are received would be the same as if station digit 10 had been dialled.

It will now be assumed that the calling subscriber dials a first digit which as described above results in the setting and subsequent release of the auxiliary switch but then abandons the call without dialling further. In this case the release of relay 110, incident to the subscriber replacing his receiver, results in the closure of the above-traced initial circuit for first-impulse-absorbing relay 170, by way of contacts 112 and 125, during the release time of relay 120, so that relay 170 operates to its first step, closing its "X" contact 172. When relay 120 also restores, ground is removed from the left-hand terminal of both windings of relay 170 at contact 125 and from the right-hand terminal of the upper winding of this relay at contact 122. Consequently, the full operation of relay 170 is prevented and this relay permitted to restore to its normal condition. Because of the failure of relay 170 to operate to its second step, the tens digit operating circuits for the two switch magnets are held open at contacts 173 and 175 and both switches accordingly remain at normal in this type of call, whereby unnecessary homing operations of these switches are avoided.

Reverting now to calls in which a second or tens digit other than 3 is dialled it will be understood from the preceding explanation that if this tens digit is 1, relay 170 operates in response to the corresponding impulse but neither switch is advanced in response thereto. Then relay 160 releases at the end of the digit relay 190 operates as above described to set the circuit for the receipt of the units digit. The connector switch accordingly is advanced from its normal position, in response to the units digit, on a one-step-per-impulse basis, whereby access is given to the corresponding line of the first group, these lines being connected to the first ten positions in the odd bank set of the connector switch.

In the example described in detail above, the second or tens digit 3, was an odd digit and since the auxiliary switch at the end of this odd tens digit rests in a position 21, in which the A2-bank of this switch is unconnected, relay 180 was left unoperated. However, if, instead of a 3, a 4 is dialled as the second digit, the auxiliary switch is arrested at the end of this digit in position 3 in which ground is wired to the A2-bank of this switch. Therefore, when relay 190 operates at the end of this digit, wiper switching relay 180 operates by way of contact 194. Relay 180 at its preliminary or "X" contact 187 locks to ground at contact 124; and at contacts 181, 182, 183, 184, and 185, 186, transfers the talking and test conductors of the connector from its odd set of wipers 80, 81; 78, 79; and 82, 83 to its even set of wipers 86, 87; 84, 85; and 88, 89 by way of conductors 232; 234; and 236 respectively. As the connector switch itself in response to tens digit 4 has been advanced to its 15th position in the manner hereinbefore described, the subsequently received units digit will further advance the connector to the cor-

responding line in tens group 4, all of these lines being connected to the even set of wipers as shown. Odd-even wiper switching relay similarly operates when tens digit 2, 6, 8 or 0 is dialled since in all these cases the auxiliary switch at the end of this digit has assumed a position, 1, 5, 7 and 9 respectively, in which ground is available in the A2-bank of the switch. In all these instances, therefore, the even set of wipers of the connector switch is made effective.

10 It remains to briefly consider the situations in which the connector switch automatically takes an additional step during the units digit. One such situation exists if 6 has been dialled as the tens digit in which case the connector switch has come to a rest in the 25th position 15 at the end of this digit. Assuming that 1 is subsequently dialled as the units digit, the switch is advanced, responsive to this digit to position 26 in the regular manner. In position 26 the following circuit including interrupter contact 71 is closed for the connector switch magnet: 20 direct ground, GCl-wiper 76 in position 26, contact 71, winding of magnet 70, to battery. The connector switch is thus rapidly stepped into its 27th position in which even wipers 79, 81, 83 engage the first contacts in the respective even contact banks, this set of contacts giving access 25 to the first line of tens group 6 as shown. This additional step is similarly taken when any of the other nine lines in tens group 6 is called.

A similar automatic stepping operation takes place when 0 is dialled as the tens digit and any of digits 6—0 30 as the units digit. As will be readily seen from the drawings, the additional step in these cases advances the switch from position 52 to position 1, namely by way of the following circuit: ground, contacts 122, 167, 176, GS-conductor 216, GC2-wiper 77 in position 52, interrupter contact 71, magnet 70, to battery.

While only one embodiment of this invention has been illustrated and described, it is to be understood that numerous modifications in the details of arrangement may be resorted to without departing from the true spirit and scope of the invention as defined in the appended claims.

What is claimed is:

1. A single-motion numerical switch having a magnet and a set of wipers and contact banks, certain of the banks of said switch having a plurality of groups of outlets connected thereto, each group having a start position, 45 said set also including a control wiper and bank, and said switch having associated therewith means responsive to a received group-selecting series of numerical impulses, odd-even control means governed by said impulse responsive means and having switching contacts, and interrupter circuits for said magnet controlled by said control wiper and bank for advancing said switch, concurrently with the receipt of said series of impulses, over positions corresponding to an unwanted group or groups to the start 50 position of the wanted group, said interrupter circuits respectively extending over a first start conductor multiplied to contacts in said control bank corresponding to the start positions of odd-numbered groups, a second start conductor multiplied to contacts in said control bank corresponding to the start positions of even-numbered groups and additional connections to said bank in the 55 positions intermediate said odd and even start positions, said odd and even start conductors being connected to said switching contacts and being alternately made effective by said contacts, each conductor on every other impulse, under the control of said impulse responsive means, and said additional connections being independent of said impulse responsive means, whereby the advancement of said numerical switch is maintained in spite of said impulse responsive means changing their condition while said switch is in said intermediate positions.

2. A single-motion numerical switch having a magnet and a set of wipers and contact banks, certain of the banks of said switch having a plurality of groups of outlets connected thereto, each group having a start posi-

tion, said set also including a control wiper and bank, and said switch having associated therewith means responsive to a received series of impulses, an auxiliary single-motion switch having a wiper and bank and being governed by said impulse responsive means and interrupter circuits for said magnet controlled by said control wiper and bank for advancing said numerical switch, concurrently with the receipt of said series of impulses, over positions corresponding to an unwanted group or groups to the start position of the wanted group, said circuits respectively extending over a first start conductor multiplied to contacts in said control bank corresponding to the start positions of odd-numbered groups, a second start conductor multiplied to contacts in said control bank corresponding to the start positions of even-numbered groups and additional connections to said bank in the positions intermediate said odd and even start positions, said odd and even start conductors being connected to alternate bank contacts of said auxiliary switch and being made effective, each conductor on every other other impulse, by the advancement of said auxiliary switch wiper under the control of said impulse responsive means, and said additional connections being independent of said impulse responsive means, whereby the advancement of said numerical switch is maintained in spite of said impulse responsive means changing their condition while said switch is in said intermediate positions.

3. A single-motion numerical switch having a magnet and a set of wipers and contact banks, certain of the banks of said switch having a plurality of groups of outlets connected thereto, each group having a start position, said set also including a control wiper and bank, and said switch having associated therewith an impulse relay responsive to a received series of impulses and having a break contact, an auxiliary single-motion switch governed by said impulse relay and having a wiper and bank and interrupter circuits for said magnet controlled by said control wiper and bank for advancing said numerical switch, concurrently with the receipt of said series of impulses, over positions corresponding to an unwanted group or groups to the start position of the wanted group, the respective interrupter circuits in the various start positions of said numerical switch extending over said break contact, said wiper and bank of said auxiliary switch and said bank and wiper of said numerical switch in series.

4. A single-motion numerical switch having a magnet and a set of wipers and contact banks, certain of the banks of said switch having a plurality of groups of outlets connected thereto, each group having a start position, said set also including a control wiper and bank, and said switch having associated therewith an impulse relay responsive to a received series of numerical impulses and having a break contact, odd-even control means governed by said impulse relay and having switching contacts, and interrupter circuits for said magnet controlled by said control wiper and bank for advancing said switch, concurrently with the receipt of said series of impulses, over positions corresponding to an unwanted group or groups to the start position of the wanted group, said interrupter circuits respectively extending over a first start conductor multiplied to contacts in said control bank corresponding to the start positions of odd-numbered groups, a second start conductor multiplied to contacts in said control bank corresponding to the start positions of even-numbered groups and additional connections to said bank in the positions intermediate said odd and even start positions, said switching contacts being interposed between said break contact and said odd and even start conductors for alternately connecting said break contact to the one and the other conductor, each conductor at the end of every other impulse, responsive to the corresponding re-operation of said impulse relay, and said additional connections being independent of said impulse relay.

5. A single-motion numerical switch having a magnet and a set of wipers and contact banks, certain of the banks of said switch having a plurality of groups of outlets connected thereto, each group having a start position, said set also including a control wiper and bank, and said switch having associated therewith an impulse relay responsive to a received series of numerical impulses and having a break contact, an auxiliary single-motion switch of the indirect-stepping type governed by said impulse relay and having a wiper and bank, and interrupter circuits for said magnet controlled by said control wiper and bank for advancing said numerical switch, concurrently with the receipt of said series of impulses, over positions corresponding to an unwanted group or groups to the start position of the wanted group, said interrupter circuits respectively extending over a first start conductor multiplied to contacts in said control bank corresponding to the start positions of odd-numbered groups, a second start conductor multiplied to contacts in said control bank corresponding to the start positions of even-numbered groups and additional connections to said bank in the positions intermediate said odd and even start positions, said auxiliary switch wiper and bank being interposed between said break contact and said odd and even start conductors for alternately connecting said break contact to the one and the other conductor, each conductor at the end of every other impulse, responsive to the corresponding re-operation of said impulse relay, and said additional connections being independent of said impulse relay.

6. A party-line connector comprising two switches of the single-motion type, a main switch and a station selector switch, each having a magnet and a plurality of wipers and contact banks including a control wiper and bank, certain of the banks of said main switch having a plurality of groups of lines connected thereto, each group having a start position, and said connector also comprising an impulse relay responsive to the receipt both of a station-selecting and a group-selecting series of impulses, the magnet of said station selector being operated under the control of said impulse relay during said station-selecting series to cause said station selector to select a desired mode of ringing and being also operated under the control of said relay during said group-selecting series, means being provided to automatically reset said station selector between said two series, and interrupter circuits for the magnet of said main switch controlled by its control wiper and bank for advancing said main switch, concurrently with the receipt of said group-selecting series of impulses, over positions corresponding to an unwanted group or groups to the start position of the wanted group, the respective interrupter circuits in the various start positions of the main switch extending over said control wipers and banks of both switches in series.

55. 7. A party-line connector comprising two switches of the single-motion indirect-stepping type, a main switch and a station selector switch, each having a magnet and a plurality of wipers and contact banks including a control wiper and bank, certain of the banks of said main switch having a plurality of groups of lines connected thereto, each group having a start position, and said connector also comprising an impulse relay having impulse contact means, said impulse relay being responsive to the receipt both of a station-selecting and a group-selecting series of impulses, the magnet of said station selector being operated under the control of said impulse contact means during said station-selecting series to cause said station selector to select a desired mode of ringing and being also operated under the control of said means during said group-selecting series, interrupter circuits being provided to automatically operate said magnet between said two series to reset said station selector, and interrupter circuits for the magnet of said main switch controlled by its control wiper and bank for advancing said main switch, concurrently with the receipt of said group-selecting series of impulses.

of impulses, over positions corresponding to an unwanted group or groups to the start position of the wanted group, the respective interrupter circuits in the various start positions of the main switch extending over said impulse contact means and said control wipers and banks of both switches in series.

8. A single-motion numerical stepping switch having a plurality of sets of wipers and banks, a member carrying said wipers, a magnet for actuating said member, groups of outlets connected to each of said sets of banks, each group having a start position, the individual start positions of a plurality of said groups in one set of banks occurring in different positions of said member with respect to the individual start positions of a plurality of said groups in another set of banks and in cyclically alternating relation with the last-mentioned individual start positions, said switch also having a control wiper and bank common to said plurality of wiper and bank sets, said control wiper also being carried by said member, and said numerical switch having associated therewith an auxiliary single-motion stepping switch having wiper and bank means also including a control wiper and bank, means responsive to the receipt of a group-selecting series of impulses for advancing said auxiliary switch, interrupter circuits for said magnet jointly controlled by said two control wipers and banks for advancing said member, concurrently with the receipt of said impulse series, to the start position of the wanted group, and circuits cyclically prepared by the wiper and bank means of said auxiliary switch during said impulse series for making the corresponding one of said wiper sets of the numerical switch effective depending upon the number of impulses in said series.

9. A single-motion numerical switch having a magnet, two sets of wipers and contact banks, a plurality of groups of outlets connected to said banks, each group having a start position, odd-numbered groups being connected to one bank set and even-numbered groups being connected to the other bank set but in staggered relation to said odd-numbered groups so that the start positions of the even-numbered groups individually alternate with the start positions of the odd-numbered groups, said switch also having a control wiper and bank common to said two wiper and bank sets, and said switch having associated therewith means responsive to a received group-selecting series of numerical impulses, odd-even control means governed by said impulse responsive means and having a pair of switching contacts, interrupter circuits for said magnet controlled by said control wiper and bank for advancing said switch, concurrently with the receipt of said series of impulses, to the start position of the wanted group, the respective interrupter circuits in successive start positions of said switch extending alternately over the one and the other of said switching contacts and being alternately made effective by said switching contacts, each in response to a separate numerical impulse, under the control of said impulse responsive means, and circuits controlled by said odd-even control means for making said odd or even wiper set effective depending upon whether the number of impulses in said series is odd or even.

10. A single-motion numerical stepping switch having a magnet, two sets of wipers and contact banks, a plurality of groups of outlets connected to said banks, each group having a start position, odd-numbered groups being connected to one bank set and even-numbered groups being connected to the other bank set but in staggered relation to said odd-numbered groups so that the start positions of the even-numbered groups individually alternate with the start positions of the odd-numbered groups, said switch also having a control wiper and bank common to said two wiper and bank sets, and said switch having associated therewith an auxiliary single-motion stepping switch having wiper and bank means also including a control wiper and bank, means responsive to the receipt of a group-selecting series of impulses for advancing said auxiliary

switch, interrupter circuits for said magnet jointly controlled by said two control wipers and banks for advancing said numerical switch, concurrently with the receipt of said impulse series, to the start position of the wanted group, and circuits controlled by the wiper and bank means of said auxiliary switch for making said odd or even wiper set effective depending upon whether the number of impulses in said series is odd or even.

11. A single-motion switch as claimed in claim 10, characterized in that said interrupter circuits respectively extend over a first start conductor multiplied to contacts in the control bank of said numerical switch corresponding to the start positions of odd-numbered groups, a second start conductor multiplied to contacts in the control bank of said numerical switch corresponding to the start positions of even-numbered groups and additional connections to said bank in the positions intermediate said odd and even start positions, said odd and even start conductors being connected to alternate contacts of the control bank of said auxiliary switch and being made effective, each conductor on every other impulse, by the advancement of the control wiper of said auxiliary switch under the control of said impulse responsive means, and said additional connections being independent of said impulse responsive means.

12. A telephone system, a calling line, a called line, a single-motion connector switch having a magnet, two sets of wipers and contact banks, each group having a start position, odd-numbered groups being connected to one bank set and even-numbered groups being connected to the other bank set but in staggered relation to said odd-numbered groups so that the start positions of the even-numbered groups individually alternate with the start positions of the odd-numbered groups, said switch also having a control wiper and bank common to said two wiper and bank sets, and said switch having associated therewith an auxiliary single-motion stepping switch having wiper and bank means also including a control wiper and bank, means responsive to a group-selecting series of impulses received under the control of said calling line for advancing said auxiliary switch, interrupter circuits for said magnet jointly controlled by said two control wipers and banks for advancing said connector switch, concurrently with the receipt of said group-selecting series and a plurality of steps per impulse, to the start position of the wanted group, circuits controlled by the wiper and bank means of said auxiliary switch for making said odd or even wiper set effective depending upon whether the number of impulses in said series is odd or even, and means effective upon termination of said group-selecting series for placing said magnet in an impulse circuit controlled by said impulse responsive means for advancing said connector switch during an impulse series subsequently received by said means on a one-step-per-impulse basis to the position corresponding to the called line.

13. A single-motion numerical switch having a magnet and a set of wipers and contact banks, certain of the banks of said switch having a plurality of groups of outlets connected thereto, each group having a start position, said set also including a control wiper and bank, and said switch having associated therewith a line relay responsive to a received group-selecting series of numerical impulses, interrupter circuits for said magnet jointly controlled by said line relay and said control wiper and bank for advancing said switch, concurrently with the receipt of said series of impulses, over positions corresponding to an unwanted group or groups to the start position of the wanted group, one of said interrupter circuits causing the switch to be advanced from its normal position, and an impulse absorbing relay also controlled by said line relay for making the last-mentioned interrupter circuit effective responsive only to the receipt of the second impulse of said series.

14. A single-motion numerical switch having a magnet and a set of wipers and contact banks, certain of the banks

of said switch having a plurality of groups of outlets connected thereto, each group having a start position, said set also including a control wiper and bank, and said switch having associated therewith means responsive to a received group-selecting series of impulses, an auxiliary single-motion switch having a wiper and bank, an impulse circuit for said auxiliary switch governed by said impulse responsive means, interrupter circuits for said magnet jointly controlled by said wiper and bank of said auxiliary switch and by said control wiper and bank of said numerical switch for advancing said numerical switch, concurrently with the receipt of said series of impulses, over positions corresponding to an unwanted group or groups to the start position of the wanted group, one of said inter-

10

rupter circuits causing said numerical switch to be advanced from its normal position, and an impulse absorbing relay also controlled by said impulse responsive means for rendering said impulse circuit and the last-mentioned interrupter circuit effective responsive only to the receipt of the second impulse of said series.
